STARTING AND STOPPING MECHANISM

Original Filed March 27, 1914

UNITED STATES PATENT OFFICE.

JESSE S. WENTWORTH, OF NORWOOD, OHIO, ASSIGNEE TO UNITED SHOE MACHINERY CORPORATION, OF PATERSON, NEW JERSEY, A CORPORATION OF NEW JERSEY.

STARTING AND STOPPING MECHANISM.

Original application filed March 27, 1914, Serial No. 827,596. Patent No. 1,336,875. Divided and this application filed October 11, 1918. Serial No. 257,727.

To all whom it may concern:

Be it known that I, JESSE S. WENTWORTH, a citizen of the United States, residing at Norwood, in the county of Hamilton and State of Ohio, have invented certain Improvements in Starting and Stopping Mechanisms, of which the following description, in connection with the accompanying drawings, is a specification, like 10 reference characters on the drawings indicating like parts in the several figures.

This invention relates to starting and stopping mechanisms, this application being a division of my co-pending application for 15 Letters Patent for improvements in assembling machines, Serial No. 827,596, filed on March 27, 1914, which issued as Patent No. 1,336,875 upon April 13, 1920.

The invention provides a novel construction 20 of starting and stopping mechanism adapted for use not only in shoe making machines of the class described in said co-pending application but also of general utility in machines of various kinds where 25 the use of mechanism of this general class may be found desirable.

An important feature of the invention 30 consists in means of novel and improved construction whereby the operator is enabled to cause the machine to be started at will and whereby the machine is stopped at the end of a definite cycle irrespective of the action of the operator, the illustrative embodiment of the invention including a simple 35 and improved construction of mechanism designed to facilitate return of the parts into their initial relation to one another in readiness for a subsequent starting operation.

40 The above and other features of the invention residing particularly in the general organization of the mechanism and in certain details of construction and combinations of parts will now be described with 45 reference to the accompanying drawings and pointed out in the claims.

In the drawings:

Figure 1 is a view in side elevation, and partly in vertical section, of mechanism in 50 which the invention is embodied;

Fig. 2 is a plan view, partly in horizontal section, of a portion of the mechanism shown in Fig. 1;

Fig. 3 is a perspective view showing a

portion of the mechanism in greater detail 55 than the other figures, and

Fig. 4 is a front elevation, partly in section, showing the mechanism controlled by the operator.

The illustrative construction comprises 60 a clutch including a driving member shown as a belt pulley 2 mounted loosely upon a shaft 4 upon which is secured a driven member comprising a frame 6. The shaft 4 may be connected, as by means of gearing 65 8, to any mechanism which is to be operated.

The pulley 2 is provided with a plurality of apertures 10 arranged in a circular series, and in the frame 6 is slidably mounted a 70 catch 12 in the form of a pin which is arranged to enter in one or another of the apertures 10 and thus operatively connect the frame 6 to the pulley. A spring 14 bearing against a trunnion block 16 on the 75 pin 12 tends to move the pin toward the pulley 2 to cause it to enter one of the apertures 10. Pivoted on the frame 6 is an arm 18 which has an opening wherein it embraces the trunnion block 16 and is connected thereto for moving the pin 12 in a direction to disengage it from the pulley. The arm 18 is provided at its other end with a laterally offset portion arranged to be engaged by a beveled surface 20 formed on a controlling member 22 comprising a bell crank pivoted at 24 on the frame of the machine. A spring 26 connected to the lower arm of the member 22 tends to maintain the member 22 in position to locate its beveled surface 20 in the path of rotary movement of the outer end of the arm 18 and thus to hold the arm normally in such position as to retract the pin 12 from engagement with the pulley 2 and permit the pulley to turn freely on the shaft 4. A rubber buffer 28 secured to the member 22 below the beveled surface 20 is arranged to engage the end of the arm 18 to stop the driven member in a definite position.

100 For operating the controlling member 22 to trip the clutch the machine is provided with a treadle 30 connected by a link 32 to a bell crank 34, an upwardly projecting arm of which is slotted to receive a pin 36 projecting laterally from a slide 38 mounted for movement back and forth in bearings in the frame. A spring 40 connected to the bell

crank 34 tends to position the parts as indicated in Fig. 1. In order to render the slide 38 effective to operate the controlling member 22 there is mounted upon the lower arm of this member an abutment 42 comprising a pivoted pawl the outer end of which is arranged to rest normally on a ledge 44 on the member 22 with the pawl inclined with respect to the path of movement of the slide 38. A spring 46 connected to the pawl 42 tends to hold it against the ledge 44. The pin 36 in the slide 38 is extended laterally into position to engage the upper surface of the pawl when the slide is moved forwardly by the action of the treadle. The pawl, bearing against the ledge 44, thus serves as an abutment to render the slide effective for swinging the member 22 into position to release the arm 18 and permit the pin 12 to be forced by the spring 14 into clutching engagement with the pulley 2.

In order to cause the driven member to be stopped at the end of a single revolution the parts are so constructed that the slide 38 in its treadle operated movement carries the pin 36 beyond the pawl 42 and thus causes the controlling member 22 to be released to the action of the spring 26 which immediately returns the member to its initial position as determined by a fixed pin 48 which engages the ledge 44. The beveled surface 20 is thus relocated in position to engage the arm 18 and withdraw the pin 12 from the pulley 2 at the end of one revolution and the buffer 28 is positioned to serve as a positive stop for the driven member. When the operator releases the treadle 30 the spring 40 serves to return the slide 38 also to its initial position, the pin 36 during this movement engaging the opposite side of the pawl 42 which yields upwardly against the tension of its spring 46 to permit the pin to pass by.

It will be seen from the above description that the pawl 42 thus acts as one form of a switch cam by means of which motion of the slide 38 is communicated to the controlling member 22. Any other suitable form of switch cam may be substituted for the pawl and still be within the scope of the invention as defined in certain of the appended claims.

Having described the invention, what I claim as new and desire to secure by Letters Patent of the United States is:

1. In mechanism of the class described, the combination with a clutch, of means for actuating said clutch comprising a clutch controlling member, a switch cam mounted on said member, an operator-controlled slide, and means on said slide arranged to engage the switch cam to operate the controlling member upon movement of the slide in one direction and to disengage the switch cam and permit the controlling member to

return to original position upon continued movement of the slide in the same direction, said slide being also arranged to engage another portion of the switch cam upon movement of the slide in the opposite direction to its original position.

2. In mechanism of the class described, the combination with a clutch, of means for actuating said clutch comprising a pivoted bell crank, a switch cam pivoted on said bell-crank, an operator-controlled slide, and means on said slide arranged to engage the switch cam to operate the bell-crank upon movement of the slide in one direction and to disengage the switch cam and permit the bell crank to return to original position upon continued movement of the slide in the same direction, said slide being also arranged to engage another portion of the switch cam upon movement of the slide in the opposite direction to its original position.

3. In mechanism of the class described, the combination with a clutch, of means for actuating said clutch comprising a clutch operating arm, a bell-crank having a beveled portion for engaging the arm to cause disengagement of the clutch, a pawl carried by said bell-crank treadle-actuated means for engaging said pawl to rock the bell-crank and remove its beveled portion from engagement with said arm to cause engagement of the clutch, and automatic means for returning the bell-crank to position to disengage the clutch.

4. In mechanism of the class described, the combination with a shaft, of a loose pulley thereon provided with a plurality of apertures, a frame fixed to the shaft, a spring-pressed pin on said frame arranged to enter any one of said apertures and clutch the pulley to the shaft, an arm pivoted to said frame for operating said pin, a bell-crank having a beveled portion for co-operatively engaging the arm to unclutch the pulley, a yieldingly-actuated pawl supported at an inclination to one arm of the bell-crank, an operator-controlled slide having a pin for engaging said pawl to rock the bell-crank and effect disengagement from said arm, and a spring for returning the bell-crank to position to effect re-engagement with said arm.

5. In mechanism of the class described, the combination with a shaft, of a loose pulley thereon provided with a plurality of apertures, a frame fixed to the shaft, a spring-pressed pin arranged to enter any one of said apertures and clutch the pulley to the shaft, an arm pivoted to said frame for operating said pin, a bell-crank having a beveled portion for co-operatively engaging the arm to unclutch the pulley, a ledge carried by an arm of the bell-crank, a pawl and yielding means for holding it against the ledge in an inclined position, an operator-

controlled slide having a pin for engaging the top of said pawl to rock the bell-crank and effect disengagement from said arm, means for returning the slide to normal position, and automatic means for returning the bell-crank to position to effect re-engagement with said arm.

6. In mechanism of the class described, the combination with a driving member and 10 a driven member, of a catch carried by the driven member and arranged to afford an operative connection between said members, an arm pivoted on the driven member for operating said catch, a controlling member 15 movable into or out of position to release said arm, and an operating member for imparting releasing movement to said controlling member, the controlling member having a part arranged to provide an abutment against which said operating member 20 acts in one direction and pivotally mounted to yield against pressure of the operating member in the reverse direction.

7. In mechanism of the class described, 25 the combination with a clutch, of means for actuating said clutch comprising a controlling member mounted for clutch tripping movement, operator-controlled means movable to operate said controlling member, 30 and an abutment pivotally mounted on said member in the path of movement of said operator-controlled means to render said means effective to operate the member, said

operator-controlled means being constructed and arranged to operate the controlling 35 member through said abutment and in its continued movement to disengage the abutment and release the member, and the abutment being arranged to swing about its pivot in response to pressure of said operator-controlled means in its reverse movement to permit said means to return to starting position.

8. In mechanism of the class described, the combination with a clutch, of means for 45 actuating said clutch comprising a pivoted bell-crank, an operator-controlled slide, a pawl pivoted on said bell-crank, means for maintaining said pawl normally in inclined relation to the direction of movement of said 50 slide and in position to serve as an abutment for transmitting movement to the bell-crank, and means on said slide arranged to engage the pawl to operate the bell-crank upon a movement of the slide in one direction and in the continued movement of the 55 slide to pass by the pawl and release the bell-crank, said pawl being yieldable in response to the pressure of said engaging means upon a movement of the slide in the 60 reverse direction to permit the parts to return to starting position.

In testimony whereof I have signed my name to this specification.

JESSE S. WENTWORTH.
